DESIGN FOR A COMBINED MIRROR AND THERMOMETER

Joseph Fischer, New York, N. Y.

Application August 2, 1939, Serial No. 86,410

Term of patent 14 years

To all whom it may concern:

Be it known that I, Joseph Fischer, a citizen of the United States, residing at New York city, county of Bronx and State of New York, have invented a new, original, and ornamental Design for a Combined Mirror and Thermometer, of which the following is a specification, reference being had to the accompanying drawing, forming part thereof.

Fig. 1 is a top plan view of a combined mirror and thermometer showing my new design;

Fig. 2 is a front elevational view of the same; and

Fig. 3 is an outer edge view of the same.

I claim:

The ornamental design for a combined mirror and thermometer, as shown.

JOSEPH FISCHER.
